ABSTRACT

The carburetor has a conventional automatic choke construction heating a bimetallic coil by engine exhaust stove heat to slowly open the choke valve during cold weather starts; a supplemental temperature responsive power means operable above a predetermined ambient temperature in response to engine acceleration demand moves the choke valve open faster, to reduce emissions.

SUPPLEMENTAL PULLDOWN MECHANISM FOR CARBURETOR AUTOMATIC CHOKE

This invention relates, in general, to a carburetor for a motor vehicle engine. More particularly, it relates to an automatic choke to provide cold weather starts of an engine, and yet good accelerations without stalls, while at the same time minimizing the output of undesirable emissions.

As ambient temperature drops, friction within the engine and the viscosity of the lubricants increase significantly. Therefore, at low temperatures, the speeds at which an engine normally would idle must be increased to prevent stalling. Accordingly, a choke mechanism is generally provided to lessen the air intake during cold starting and pre-engine warmup to insure a richer mixture.

Generally, the choke apparatus includes a coiled thermostatic spring that operatively rotates the choke valve towards a closed or nearly shut position with decreasing temperatures, and progressively opens it as the temperature returns towards a chosen level. A manifold suction responsive device generally cracks open the choke a predetermined amount when the engine starts. The choke action provides a rich mixture so that sufficient fuel can be vaporized to permit smooth cold weather starting and running of the engine.

The above construction, while generally satisfactory, is a compromise between good cold weather running conditions on the one hand and low emission outputs on the other hand. The richer than normal mixture existing during the choking operation may be richer than is necessary, which may result in higher emission outputs.

It is an object of this invention to provide an automatic choke construction that will provide good cold weather starting characteristics, provide good accelerations without stall, and yet reduce to a minimum the output of undesirable smog producing elements.

It is another object of the invention to provide an automatic choke construction that provides a leaner than conventional air/fuel mixture after the start of a warm engine in response to engine acceleration demand by pulling open the choke valve faster than would be by conventional choke systems.

It is also an object of the invention to provide an automatic choke construction including a temperature responsive, delayed action servo operable above a predetermined ambient temperature as controlled by the engine throttle valve to shorten the length of time required for the normal operation of an automatic choke.

Another object of the invention is to provide an automatic choke construction including a thermostatically controlled bimetal spring normally urging the choke valve closed with decreasing ambient temperature changes and opposed by a manifold suction operated motor device that initially cracks open the choke valve to a predetermined amount permitting running operation during cold weather with a rich mixture; engine exhaust manifold heat being directed to the spring coil to warm it; and, a supplemental vacuum operated servo operable at ambient temperatures above a predetermined level during engine acceleration modes to positively open the choke valve earlier than would normally be the case, the supplemental servo including a temperature actuated valve permitting the application of man-

ifold vacuum upon opening of the throttle valve to pull the choke valve open, the vacuum acting through a parallel path including a one-way check valve to prevent choke valve reapplication during low vacuum, and a restriction that allows recycling of the servo.

Other objects, features and advantages of the invention will become more apparent upon reference to the succeeding detailed description thereof, and to the drawings illustrating a preferred embodiment thereof; 10 wherein

FIG. 1 is a cross-sectional elevational view of a portion of a two-barrel carburetor embodying the invention;

FIG. 2 is a perspective view of a carburetor with the 15 automatic choke of the invention;

FIG. 3 is a side elevational view of a portion of the FIG. 2 showing, with parts broken away and in section;

FIG. 4 is an enlarged cross-sectional view of a detail 20 of FIG. 3; and,

FIG. 5 is a cross-sectional view taken on a plane indicated by and viewed in the direction of the arrows 5-5 of FIG. 4.

FIG. 1 is obtained by passing a plane through approximately one-half of a known type of two-barrel, down-draft type carburetor. The portion of the carburetor shown includes an upper air horn section 12, an intermediate main body portion 14, and a throttle valve flange section 16. The three carburetor sections are secured together by suitable means, not shown, over an intake manifold indicated partially at 18 leading to the engine combustion chambers.

Main body portion 14 contains the usual air-fuel mixture induction passages 20 having fresh air intakes at 35 the air horn ends, and connected to manifold 18 at the opposite ends. The passages are each formed with a main venturi section 22 containing a booster venturi 24 suitably mounted for cooperation therewith, by means not shown.

Airflow through passages 20 is controlled in part by a choke valve 28 unbalance mounted on a shaft 30 rotatably mounted on side portions of the carburetor air horn, as shown. Flow of fuel and air through each passage 20 is controlled by a conventional throttle valve 36 fixed to a shaft 38 rotatably mounted in flange portion 16. The throttle valves are rotated in a known manner by depression of the vehicle accelerator pedal, and move from an idle speed position essentially blocking flow through passage 20 to a wide open position essentially at right angles to the position shown.

The rotative position of choke valve 28 is controlled by a semi-automatically operating choke mechanism 40. The latter includes a hollow housing portion 42 that is formed as an extension of the carburetor throttle flange. The housing is apertured for supporting rotatably one end of a choke lever operating shaft 44, the opposite end being rotatably supported in a casting 46. A bracket or lever portion 48 is fixed on the left end portion of shaft 44 for mounting the end of a rod 52 that is pivoted to choke valve shaft 30. It will be clear that rotation of shaft 44 in either direction will correspondingly rotate choke valve 28 to open or close the carburetor air intake, as the case may be.

An essentially L-shaped thermostatic spring lever 54 has one leg 56 fixedly secured to the opposite or right-hand end portion of shaft 44. The other leg portion 58 of the lever is secured to the end 59 of a coiled thermo-

static spring element 60 through an arcuate slot, not shown, in an insulating gasket 61. The opposite end portion 62 of the spring is fixedly secured on the end of a nipple 64 that is formed as an integral portion of a choke cap 66 of heat insulating material. Nipple 64 is bored as shown to provide hot air passages 68 and 70, passage 68 being connected to an exhaust manifold heat stove, for example. Cap 66 is secured to housing 42 by suitable means, such as the screw 72 shown, and defines an air or fluid chamber 74 within the two.

As thus far described, it will be clear that the thermostatic spring element 60 will contract or expand as a function of the changes in ambient temperature conditions of the air entering tube 68, or, if there is no flow, the temperature of the air within chamber 74. Accordingly, changes in ambient temperature will rotate the spring lever 54 to rotate shaft 44 and choke valve 28 in one or the other directions, as the case may be.

The leg 56 of spring lever 54 is pivotally fixed to the rod 76 of a piston 78. The latter is movably mounted in a bore 79 in housing 42. The under surface of piston 78 is acted upon by vacuum in a passage 80 that is connected to the carburetor main induction passages 20 by a port 82 that is located just slightly below throttle valve 36. Piston 78, therefore, is always subject to the vacuum existing in the intake manifold passage portion 18.

As is known, a cold weather start of a motor vehicle requires a richer mixture than a warmed engine start because considerably less fuel is vaporized. Therefore, the choke valve is shut or nearly shut to increase the pressure drop thereacross and draw in more fuel and less air. Once the engine does start, however, then the choke valve should be opened slightly to lean the mixture to prevent engine flooding as a result of an excess of fuel.

The known choke mechanism described automatically accomplishes the action described. That is, on cold weather starts, the temperature of the air in chamber 74 will be low so that spring element 60 will contract and rotate shaft 44 and choke valve 28 to a closed or nearly closed position, as desired. Upon cranking the engine, vacuum in passage 80 will not be sufficient to move piston 78 to open the choke valve. Accordingly, the engine will be started with a rich mixture. As soon as the engine is running, high vacuum in passage 80 moves piston 78 downwardly and rotates shaft 44 a slight amount so that choke valve 28 is slightly opened so that less fuel is admitted to induction passage 20. Shortly thereafter, the exhaust manifold stove air in line 68 will become progressively warmer and cause choke element 60 to unwind slowly and rotate shaft 44 and choke valve 28 to a more open position. Further details of construction and operation are not given since they are known and believed to be unnecessary for an understanding of the invention.

FIG. 2 shows the carburetor as including a supplemental choke valve pulldown servo device 90 that is connected to the choke rod lever 48. More specifically, and referring to FIGS. 2-5, the servo 90 has a three piece housing consisting of a left-hand vacuum line adapter portion 92, a main body portion 94, and a cup shaped shell portion 96.

Portion 92 has a press fit within an annular flange 98 projecting from body portion 94, and contains a vacuum passage 100, with an orifice 101.

Body portion 94 contains an annular flange 122 and a central vacuum passage 124. A Belleville type bimetal disc 126 is floatingly mounted within flange 122, and is biased towards the left by a spring 128. The central portion of disc 126 has an elastomeric valve 130 fixed to it that is adapted to seat against the passage 124 to control flow through it. In assembly, an enlarged flexible integral portion 132 of the valve is pulled through a small hole 131 in disc 126 until the valve is seated, as shown.

The bimetal disc 126 is responsive to ambient temperature changes of the servo to flip over-center from the full line position shown, to the dotted line position 133, in a known manner, at say, temperature levels 15 above 65°, for example, to open passage 124. Reduction of the ambient temperature below the predetermined level will again flip-flop the disc to close passage 124.

The disc spring 128 is seated against a cup shaped spring retainer 134. The latter is held in place in the ring flange 122 by a ring 136, and has a central aperture 138.

The housing portions 94 and 96 together define a hollow interior. Between them is clamped the edge of an annular flexible diaphragm 140 that divides the interior into an air chamber 142 and a vacuum chamber 144. Holes 145 in housing portion 96 permit a free communication of chamber 142 with the ambient air pressure surrounding the servo.

A pair of retainers 146 fixedly mount a plunger or link 148 on the diaphragm, a spring 150 normally biasing the plunger to the position shown. The plunger has a lost motion connection to choke lever 48 consisting of an elongated slot 152 that receives the bent end 154 of a link 156 pivotally connected to lever 48.

A pair of bosses 158 are welded to housing portion 96 for the attachment of a mounting bracket 160 that is secured at its opposite end to a portion of the throttle valve body portion of the carburetor, as shown.

In this case, as best seen in FIG. 3, a tube 102 connects servo vacuum line 100 to a vacuum port 162 through a flow control device 164. The port 162 opens into the carburetor induction passage 20 at a location above the cold fast idle position of the throttle valve 36. This is so vacuum will not be applied to line 102 until the engine is accelerated, in a manner to be described later, and will be cut off when the throttle valve is returned to its idle speed position.

The control device 164 is shown schematically, and constitutes a check valve assembly. It has a hollow casting 166 with a central partition 168 having two holes 170 and 172. A flexible elastomeric umbrella type check valve 174 controls flow through hole 170, while a sintered metal restrictor 176 controls flow through hole 172. As will become more clear later, once servo 90 has opened the choke valve, low vacuums at port 162 will close check valve 174 to prevent a reclosing of the choke, while the restrictor 176 permits a bleed-down of vacuum in servo 90 and a restroking of the servo after engine shutdown.

In operation, below 65°F ambient, the bimetal disc 126 remains in a valve closed position as shown, and no vacuum is applied from passage 100 into servo chamber 144 regardless of the position of throttle valve 36. Therefore, the servo is inoperative. The choke valve is initially closed by coil 60, and cracked open upon engine startup by the pulldown servo 78. Increases in

choke housing temperature, caused by the increases in exhaust manifold heat, cause the bimetal 60 to unwind slowly and permit opening of the choke valve by airflow against it. This is permitted by the sliding movement of the pin 154 in slot 152. The entire choking action will then be controlled solely by the coil 60.

Assume now that the ambient temperature is above 65°F. Vacuum now can be applied directly to chamber 144 because the thermostatically responsive disc 126 has now flipped over center to position 133. Check valve 174 will open because of the pressure differential acting on opposite sides. Accordingly, when the throttle valve 36 is moved to an open engine acceleration position beyond the cold fast idle position shown, the vacuum port 162 becomes exposed to manifold vacuum. Thus, with servo disc 126 in position 133, vacuum in line 102 unseats valve 130 and opens passage 124. Manifold vacuum in passage 100 now is applied to begin drawing diaphragm 140 and plunger 148 to the left. This will continue without any effect on the choke valve until the pin 154 is engaged by the end of slot 152. Continued leftward movement of the plunger until it bottoms, at dotted line position 162, against retainer 134, will then positively open the choke valve against the force of the coil 60.

The maximum delay in the system that occurs is determined by the size of orifice 101 and approximately 2 to 3 seconds, long enough so that the choke valve will come off after the engine acceleration. This provides a richer mixture during the initial tip in accelerating movement of the throttle valve.

Assume now that the engine is shut off so that the manifold vacuum decays suddenly. It is desirable at this time that the servo 90 recycle itself so as to be in a position to provide the desired choking action when restarted. The sintered metal bleed provides this action by bleeding the vacuum in chamber 144 to atmospheric pressure in line 102.

In summary, therefore, below an ambient temperature level of $65^{\circ}\pm F$, the choke hot air system provides the only control for choking functions. The bimetal coil 60 will unwind, therefore, only as a function of the increased heating by the hot air from passage 68.

Above 65°F, however, the conventional exhaust manifold stove heat system constitutes the primary choke control, while the vacuum operated servo device 90 acts as the supplemental force to pull open the choke valve faster than were it being controlled by the primary control alone. This leans the fuel/air mixture earlier than with conventional choke arrangements, and lowers undesirable emission outputs. Control of the pulloff of the choke by the throttle valve prevents stalling during acceleration modes of operation, and the check valve prevents the choke from being re-applied during low vacuum operating conditions.

With the above described choke construction, therefore, it will be seen that it is possible to provide a reliable and accurate short duration choking effect thereby minimizing vehicle exhaust emission without jeopardizing the cold weather choking function.

We claim:

1. An automatic choke system for use with a carburetor having an air/fuel induction passage and an unbalance mounted, air movable, choke valve mounted for variable movement across the passage to control airflow through the passage,

a throttle valve mounted for a rotatable movement across the induction passage to open and close the same,

thermostatic spring means operably connected to the choke valve urging the choke valve towards a closed position with a force increasing as a function of decreases in the temperature of the spring means from a predetermined level,

and a vacuum actuated, spring returned servo operable on the choke valve in opposition to the thermostatic spring means to at times override the choke valve closing force of the thermostatic spring means and actuate the choke valve to an open ineffective position, conduit means connecting a portion of the servo to a port in the induction passage at a location above the cold idle speed, slightly open, position of the throttle valve so as to be subjected to ambient pressure during operation of the throttle valve in the cold idle speed position and subjected increasingly to engine intake manifold vacuum as the throttle valve is moved progressively across the port towards a position more open than the cold idle speed position indicative of an engine accelerating condition.

2. A choke system as in claim 1 including temperature responsive means in the conduit means for closing the conduit means below a predetermined temperature level.

3. A choke mechanism as in claim 1, including time delay means in the conduit means to control the application of pressure and vacuum to the servo.

4. A choke system as in claim 1, including time delay means in the conduit means to delay the bleed of vacuum from the servo upon opening of the throttle valve providing vacuum levels at the induction passage lower than at the servo, and one-way check valve means in parallel with the delay means in the conduit means for bypassing the delay means during reverse vacuum conditions.

5. A two phase automatic choke system for use with a carburetor having an air/fuel induction passage open at one end and adapted to be connected to an engine intake manifold at the other end for subjecting the passage to varying manifold vacuum, the passage having a throttle valve mounted for a variable movement between positions opening and closing the passage to control air/fuel flow through it,

the choke system including an unbalance mounted, air movable, choke valve mounted anterior of the throttle valve for variable movement across the passage to control air flow towards the throttle valve,

bimetallic thermostatic spring means operably connected to the choke valve urging the choke valve towards a closed position with a force increasing as a function of decreases in the temperature of the spring means from a predetermined level,

first power means sensitive to engine manifold vacuum for moving the choke valve towards a partially open position in opposition to the spring means, and supplemental vacuum sensitive power means in a parallel power flow arrangement with the first power means for effecting subsequent movement of the choke valve towards a position more open than the position effected by the first power means,

the supplemental means including a vacuum servo having a vacuum chamber and an ambient pressure chamber defined by a movable diaphragm, a plunger secured to the diaphragm, lost motion means connecting the plunger to the choke valve, conduit means connecting a port in the induction passage to the servo vacuum chamber, the port being located above the cold idle speed position of the throttle valve and adapted to be traversed by the valve during its movement to an open engine accelerating position beyond the cold idle speed position, the change in pressure in the vacuum chamber upon change in pressure in the conduit

means, to maintain the movement of the supplemental means during low vacuum conditions at the vacuum port.

5 6. An automatic choke construction as in claim 5, including on-off temperature responsive valve means in the conduit means movable to block flow of vacuum to the servo chamber below a predetermined ambient temperature.

10 7. An automatic choke system as in claim 5, the last mentioned control means comprising a flexible check valve.
